RAILWAY TRAFFIC CONTROLLING APPARATUS

Earl M. Allen, Swissvale, Pa., assignor to The Union Switch & Signal Company, Swissvale, Pa., a corporation of Pennsylvania

Application July 31, 1941, Serial No. 404,763

5 Claims. (Cl. 246—134)

My invention relates to railway traffic controlling apparatus, and more particularly to such apparatus for controlling the signals of a traffic route over which traffic may move in either direction.

Signals located at the opposite ends of a traffic route for controlling traffic in opposite directions over the route may be controlled by an interlocking, a remote control system or a centralized traffic control system. Whatever the system of control used, it is essential that each switch within the limits of the route be properly set before a signal can be cleared. Also it is desirable to prevent a so-called "hidden lockout" condition. Such "hidden lockout" may occur if an operator transmits a control influence for clearing a signal and such signal fails to respond for any reason to such control influence and the operator overlooks this condition and fails to transmit a control influence to cancel the control established by the first transmitted influence. This control condition established by the first influence remains stored and keeps in effect the electric locking against other signals associated with the first mentioned signal. Such electric locking becomes hard to locate because the operator has overlooked his neglect to cancel the control influence that caused it, and for this reason such lockout is commonly referred to as a "hidden lockout," all signals for the respective route being of course inoperative as long as this lockout exists. Again, when a signal at one end of the route has been cleared, it is essential that any inadvertent attempt on the part of the operator to clear the opposing signal is prevented from setting the cleared signal to stop. Furthermore, at interlockings it is desirable to prevent the establishing of a control for clearing the signal for a train to move over a route that conflicts with a route already in use. That is, it is essential that a train cannot be directed over a wrong route.

In view of such circumstances in railway traffic controlling apparatus, a feature of my invention is the provision of railway traffic controlling apparatus incorporating novel means for controlling the opposing signals of a route over which traffic may move in either direction.

Another feature of my invention is the provision of railway traffic controlling apparatus incorporating novel means for preventing a so-called "hidden lockout" condition in the control of signals of a traffic route.

Again, a feature of my invention is the provision of apparatus of the type here involved

wherewith the establishing of a control for a signal for a wrong route is avoided.

Other features, objects and advantages of my invention will become apparent from the following specification.

The above features, objects and advantages of my invention are attained by providing a route relay at each end of a traffic route over which traffic may move in either direction, and by controlling each such route relay over a pick-up circuit and a stick circuit, which circuits in turn are governed by manually controlled means one for each end of the route. A pick-up circuit for a route relay is formed only when the manually controlled means at the same end of the route is operated, the route is properly conditioned for traffic, the signals are at stop, and the manually controlled means at the opposite end of the route is at its normal condition. The stick circuit for each route relay is closed only when the signal governed by that relay is cleared. The control influence for closing a pick-up circuit for a route relay continues for a predetermined time interval only and hence if the intended signal fails to clear during such time interval the control influence becomes non-effective. Thus when a manually controlled device or means is operated to close the pick-up circuit for a route relay and such control influence persists for a predetermined time interval only, the route relay is not retained energized by its stick circuit when the signal fails to clear, and the control influence is annulled. In other words, there is no storing of the control influence or code for clearing a signal with the result that a so-called "hidden lockout" condition is avoided. Also by such stick circuit control for a route relay that governs a signal at the corresponding end of a traffic route, a signal once cleared to permit a movement into the route is not set to stop by any inadvertent operation of the manually controlled means at the opposite end of the route.

I also provide a check or repeater relay which is controlled by the controlling relays for each switch of the traffic route as well as by indication and repeater relays controlled by the switch, such special check or repeater relay being energized only when there is agreement in the positions of the controlling and repeater relays associated with a switch. Contacts of such check relay are interposed in the pick-up circuit of the associated route relays. Hence if an operator after preparing a route for a train, erroneously attempts to clear a signal for the train to move over a wrong route, the route relays for such

wrong route cannot respond to the control influence and the train is not directed to the wrong route.

I shall describe one form of apparatus embodying my invention, and shall then point out the novel features thereof in claims.

In the accompanying drawings, Fig. 1 is a diagrammatic view showing a typical track layout which the apparatus of my invention is adapted to control. Figs. 2 to 7, inclusive, when taken together constitute a diagrammatic view showing one form of apparatus embodying my invention arranged for governing the switches and signals of the track layout of Fig. 1. Similar reference characters refer to similar parts in each of the several views.

Referring to Fig. 1, while a specific track layout is disclosed, it is to be understood that the apparatus of my invention is adapted to control other track layouts that may involve entirely different combinations of switches and signals, the relatively simple layout shown, however, being adequate to illustrate the principles of my invention. Fig. 1 illustrates by a single line diagram, a stretch of double track railway the two tracks EB and WB of which are connected by a crossover 3. The movement of traffic over crossover 3 is governed by signals bearing the reference characters 2 and 8 with distinguishing prefixes of R and L to indicate the direction of traffic governed by the signal. According to standard practice, signals L2 and R8 are each provided with but one signal mechanism, while signals L8 and R2 are each provided with two signal mechanisms mounted on the same mast, signal L8 being provided with signal mechanisms LA8 and LB8, and signal R2 being provided with signal mechanisms RA2 and RB2. Thus when crossover 3 occupies its normal position, signals R8 and LA8 are opposing signals for a route on track WB, signals L2 and RA2 are opposing signals for a route on track EB, and when crossover 3 occupies its reverse position, signals RB2 and LB8 are opposing signals for a route for traffic to move from track WB to track EB or vice versa.

The rails of tracks EB and WB are formed into track sections by the usual insulated rail joints, section 4T of track EB and section 7T of track WB including the respective switches of crossover 3 and extending from one to the other of the respective opposing signals. The adjacent approach track sections are indicated by the reference characters R2T, R8T, L2T and L8T, respectively. Each section is provided with a track circuit including a normally energized track relay, each track relay being identified by the reference character R with a prefix indicating the track section.

In order to simplify the drawings and to enable the circuits to be more readily traced, I have located in most instances the relay contacts remote from the winding of the relay, and contacts of the usual controllers operated by the switches 3E and 3W of the crossover remote from the switch. In each such case, the contact is identified by the reference character of the associated operating device as well as by a distinctive number. Also each such contact is shown in a position corresponding to the normal position of the operating device.

Switches 3E and 3W of crossover 3 are actuated by power switch machines 3SM and 3ASM, respectively. The type of switch machine is immaterial, and they are shown in the drawing conventionally. It is sufficient for the present ap-

plication to point out that each switch machine includes a motor element and a driving mechanism by which the motor element is operatively connected to the switch so that when the motor element is energized over a first or normal operating circuit the mechanism is operated as required to move the switch to its normal position, and when the motor element is energized over a second or reverse operating circuit, the mechanism is operated as required to move the switch to its reverse position. The two switch machines are interconnected so that the two ends of the crossover agree in their positions. As shown in Fig. 1, a normal operating circuit can be traced from terminal B of a convenient source of current, such as a battery not shown, over front contact 4 of a normal switch controlling relay 3NWS to be referred to later, wire 5, motor element of switch machine 3SM and wire 6 to terminal C of the same source of current. This normal operating circuit extends from switch machine 3SM over wire 7 to the motor element of switch machine 3ASM and wire 8 to terminal C. A reverse operating circuit includes terminal B, front contact 9 of a reverse switch controlling relay 3RWS, also to be referred to later, wire 10, motor element of switch machine 3SM, wire 6 and terminal C; and this circuit extends from switch machine 3SM over wire 11, through the motor element of switch machine 3ASM and wire 8 to terminal C. Hence when normal switch controlling relay 3NWS is picked up, the crossover 3 is actuated to its normal position, and when reverse switch controlling relay 3RWS is picked up, the crossover is actuated to its reverse position. The means for controlling relays 3NWS and 3RWS will be later described.

Referring to Fig. 2, the switches of crossover 3 govern a switch indication relay 3KR and switch repeater relays 3NKP and 3RKP according to the positions of the switches. A normal energizing circuit for relay 3KR is formed from terminal B over contacts 12 and 13 of the usual circuit controllers of switches 3E and 3W, respectively, and which contacts are closed at the normal position of the switches, winding of relay 3KR, contacts 14 and 15 of the respective circuit controllers and terminal C. This circuit energizes relay 3KR at normal polarity to close its front neutral contact 16 and its normal polar contact 17. With the two switches occupying their reverse positions, a circuit is formed from terminal B over contact 18 of the controller for switch 3E, contact 14 of the controller for switch 3W, winding of relay 3KR, contacts 13 and 19 of the respective controllers and to terminal C, and relay 3KR is energized at reverse polarity to close its front contact 16 and reverse polar contact 20. Relay 3KR in turn controls repeater relays 3NKP and 3RKP, the arrangement being such that normal switch repeater relay 3NKP is energized over an obvious circuit including front contact 16 and normal polar contact 17 of relay 3KR, and reverse switch repeater relay 3RKP is energized over an obvious circuit including front contact 16 and reverse polar contact 20 of relay 3KR. As also shown in Fig. 2, the switch repeater relays 3NKP and 3RKP, together with switch controlling relays 3NWS and 3RWS, govern another repeater or check relay 3WPZ. When switch controlling relay 3NWS is picked up to close the normal switch operating circuit as shown in Fig. 1 and normal switch repeater relay 3NKP is picked up due to the normal position of the switches 3E and 3W of the

crossover, a circuit is formed from terminal B over front contact 21 of relay 3NKP, front contact 22 of relay 3NWS, back contact 23 of relay 3RWS, winding of relay 3WPZ and to terminal C, and relay 3WPZ is picked up. Again, when the reverse switch controlling relay 3RWS is picked up to complete the reverse switch operating circuit as shown in Fig. 1, and repeater relay 4RKP is picked up in response to the reverse position of the switches of the crossover, a circuit is formed from terminal B over back contact 24 of relay 3NKP, front contact 25 of relay 3RKP, front contact 26 of relay 3RWS, winding of relay 3WPZ and to terminal C, and relay 3WPZ is picked up. It follows that the check or repeater relay 3WPZ is picked up when there is agreement in position between the switch controlling relays of crossover 3 and the switch repeater relays governed by the switches of the crossover. The relays 3NKP, 3RKP and 3WPZ, control the route locking circuit of Fig. 7 to be described hereinafter.

Referring to Fig. 3, an approach locking relay M is provided for each direction of traffic of each track EB and WB, the circuit for each such approach locking relay being substantially that in present day use and a description of the circuit for one such relay will suffice for an understanding of all. For example, approach locking relay R2M associated with eastbound traffic on track EB is controlled by a circuit formed from terminal B over front contact 124 of a signal repeater relay R2GP to be referred to later, back contact 125 of a route relay R2HS also to be referred to later, front contact 126 of track relay R2TR, winding of relay R2M and to terminal C. If signal repeater relay R2GP is released or route relay R2HS is picked up, approach locking relay R2M is released. In the event the approach section R2T is occupied and signal R2 put to stop by the release of route relay R2HS in a manner to be later described, relay R2GP is picked up, relay R2M is reenergized over a circuit including a front contact 27 of a time element relay 2TE. Relay 2TE will become energized over a circuit including terminal B, front contact 124 of relay R2GP, back contact 125 of relay R2HS, back contact 28 of relay R2M, winding of relay 2TE and terminal C. Relay 2TE is energized after a predetermined time interval and picks up to close front contact 27 and cause relay R2M to be energized. If signal R2 is put to stop automatically by the passage of a train into section 1T shunting track relay 1TR and causing relay R2HS to be released as will later appear, the circuit of relay R2M is completed at back contact 29 of track relay 1TR of section 1T. The control circuit for approach locking relay R8M associated with eastbound movement on track WB, relay L8M associated with westbound movement on track WB and relay L2M associated with westbound movement on track EB will be readily understood from an inspection of Fig. 3 taken in connection with the description of the control circuit for relay R2M. These approach locking relays M are used not only in the usual manner to approach lock the switches of the crossover, but are also used to control the respective signal control networks as will be apparent when the signal control networks of Fig. 6 are described.

The signals shown in Fig. 1 may be of any suitable type and in accordance with standard practice the signals RA2 and LA2 govern high speed routes and will be the usual three-position

signals governed in accordance with the condition of other signals in advance, not shown, in addition to being subject to manual and track circuit control. The remaining signals RB2, R8, LB8 and L2 govern low speed routes and are two-position signals and are subject to manual and track circuit control. In the present embodiment of the invention, these signals are considered as being of the color light type, the operating or lighting circuits of each signal being governed by a signal control relay identified by the reference character H with a prefix corresponding to the respective signal.

Looking at Fig. 4, the operating circuits for signal RA2 are governed by a signal control relay RA2H and the circuits for signal RB2 are governed by a signal control relay RB2H. When relay RA2H is picked up to close its front contact 30 and a relay R2D controlled by signals in advance is picked up to close front contact 31, the G lamp of signal RA2 is illuminated as a clear signal indication. If relay RA2H is picked up to close front contact 30 and relay R2D is released closing back contact 32, the Y lamp of signal RA2 is illuminated as an approach signal indication, and when relay RA2H is released to close back contact 33, the R lamp of signal RA2 is illuminated as a stop signal indication. Again, when relay RB2H is picked up to close front contact 34, the Y lamp of signal RB2 is illuminated and when relay RB2H is released closing back contact 35 the R lamp of signal RB2 is illuminated. The operating circuits for illuminating the different lamps of the other signals will be apparent from an inspection of Fig. 4 taken in connection with the above description of the circuits of signals RA2 and RB2.

Referring to Fig. 5, a signal repeater relay is provided for each signal of Fig. 1, such repeater relay being identified by the reference character GP with a prefix corresponding to the signal. For example, the signal repeater relay R2GP for signal R2 is normally energized over a circuit including terminal B, back contacts 36 and 37 of signal control relays RB2H and RA2H, respectively, winding of relay R2GP and terminal C. The signal repeater relay R8GP for signal R8 is controlled over back contact 38 of signal control relay R8H; repeater relay L2GP for signal L2 is controlled over back contact 39 of signal control relay L2H; and repeater relay L8GP for signal L8 is controlled over back contacts 40 and 41 of signal control relays LB8H and L8SH, respectively. It follows that when a signal control relay is released to set the corresponding signal to stop, the respective signal repeater relay is picked up and when the signal control relay is picked up to operate its corresponding signal to a proceed position, the respective repeater relay is released.

The signal control relays H are controlled over circuit networks illustrated in Fig. 6, the circuit network for each signal control relay H being controlled over front contacts of a route relay HS for the corresponding signal and by a back contact of the route relay HS associated with the opposing signal, such route relays being controlled by the circuit network of Fig. 7 shortly to be described. The signal control relay network is a counterpart of the track layout and includes a circuit for each direction for each route through the layout, each circuit being formed by conductors corresponding to portions of the track and connected together by contacts

controlled in accordance to the positions of the track switches. The circuit for each signal control relay also includes a front contact of the approach locking relay M associated with the opposing signal, thereby not only insuring that the signal cannot be cleared until the opposing signal indicates stop, but also interposing a time delay in the reversing of the direction of traffic over a route when a signal is put to stop in the face of an approaching train.

Assuming the crossover 3 is normal and section 1T of track EB is unoccupied, signal control relay RA2H is energized if route relay R2HS associated with signal RA2 is picked up and route relay L2HS associated with signal L2 is released. The circuit for relay RA2H includes terminal B, front contact 42 of opposing approach locking relay L2M, back contact 43 of opposing route relay L2HS, back contact 44 of relay 2TE, normal polar contact 45 and front neutral contact 46 of indication relay 3KR, front contact 47 of route relay R2HS, back contact 48 of relay R2M, front contact 49 of track relay 1TR, front contact 50 of switch repeater relay 3NKP, winding of relay RA2H, front contact 51 of route relay R2HS and terminal C. It is clear that in the event route relay L2HS is picked up in place of relay R2HS, the signal control relay L2H is provided with a circuit including terminal B, front contact 52 of relay R2M, back contact 53 of relay R2HS, contacts 46, 45 and 44, front contact 54 of relay L2HS, back contact 55 of relay L2M, front contact 56 of relay 1TR, winding of relay L2H, front contact 57 of relay L2HS and terminal C.

In the event crossover 3 occupies its normal position, and section 7T of track WB is unoccupied, and route relay L8HS associated with signal L8 is picked up, signal control relay LA8H is energized over a circuit extending from terminal B, front contact 58 of the opposing approach locking relay R8M, back contact 59 of the opposing route relay R8HS, normal polar contact 60 and front contact 61 of relay 3KR, back contact 62 of relay 8TE, front contact 63 of relay L8HS, back contact 64 of relay L8M, front contact 65 of relay 7TR, front contact 66 of relay 3NKP, winding of relay LA8H, front contact 67 of relay L8HS and to terminal C. In the event route relay R8HS associated with signal R8 is picked up then the signal control relay R8H is provided with a circuit including terminal B, front contact 68 of relay L8M, back contact 69 of relay L8HS, contacts 62, 61 and 60, front contact 70 of relay R8HS, back contact 71 of relay R8M, front contact 72 of relay 7TR, winding of relay R8H, front contact 73 of relay R8HS and terminal C.

Assuming that crossover 3 occupies its reverse position to establish the route from signal LB8 to signal RB2, and sections 7T and 1T are unoccupied and the route relay L8HS associated with signal L8 is picked up, signal control relay LB8H is provided with a circuit that extends from terminal B over front contact 52 of relay R2M, back contact 53 of relay R2HS, front contact 46 and reverse polar contact 74 of indication relay 3KR, back contact 62 of relay 8TE, front contact 63 of relay L8HS, contacts 64 and 65, front contact 75 of relay 1TR, front contact 76 of reverse switch repeater relay 3RKP, winding of relay LB8H, front contact 67 of relay L8HS and to terminal C. In the event route relay R2HS is picked up with crossover 3 in its reverse position, then the signal control relay RB2H is provided with a cir-

cuit that includes terminal B, contacts 68, 69, 62, 74, 46, 47, 48, 49, 77, 78, winding of relay RB2H, front contact 51 of relay R2HS and terminal C. It is to be seen therefore that each signal control relay is picked up for operating the corresponding signal to a proceed position when the associated route relays, the track relays for the sections of the route, the associated approach locking relays, and the repeater and indication relays for the switches of the route are all properly positioned.

The circuits for the route relays HIS which govern the networks of Fig. 6 are shown in Fig. 7. Each traffic route is provided with two route relays, one for each end of the route. The two route relays of a route are controlled by two manually controlled means one for each end of the route and by the repeater relays for the switches and signals of the associated route. Such manually controlled means may be levers of an interlocking machine, relays of a relay type of interlocking or relays of a remote control or centralized traffic control system. In the present embodiment of the invention the manually controlled means comprise relays of a centralized traffic control system of a suitable code type and which system is provided with coding units through which relays are selectively controlled according to different codes transmitted from a remote office, there being a coding unit CU1 associated with the left-hand end of the track layout of Fig. 1, and a unit CU2 associated with the right-hand end of the track layout. A pair of code responsive relays is provided in each coding unit for controlling the circuit network of each route relay, such code responsive relays being identified by the reference character L with a distinguishing prefix. For example, route relay R2HS used to control the signal control relays of signal R2 is controlled by a normal code responsive relay NR2L and by a reverse code responsive relay RR2L of the coding unit CU1. Similarly, route relay R8HS used to control signal R8 is controlled by a normal code relay NR8L and a reverse code relay RR8L of unit CU1. At coding unit CU2, normal code relay NL8L and reverse code relay RL8L govern route relay L8HS which in turn is used to control signal L8, and normal code relay NL2L and reverse code relay RL2L govern route relay L2HS which is associated with signal L2.

While the centralized traffic control system may use any one of several different types of codes by which each unit and a particular relay of the unit are selected it is contemplated that each code relay L is biased to a released position and is energized and picked up during the transmission of the code impulse that selects the relay and the relay is then released when the code impulse ceases. The arrangement is such that each code relay is retained picked up for a predetermined time interval which ordinarily may be of the order of a few seconds. Each route relay is energized over a pick-up circuit and a stick circuit, which circuits in turn are controlled by the associated code relays at the two ends of the associated route.

Assuming the crossover 3 occupies its normal position, the route relays R2HS and L2HS are associated with the opposite ends of the route between signals R2 and L2. To select route relay R2HS for establishing traffic from signal R2, code relay RR2L is selected by the appropriate code and relay RR2L when picked up forms a pick-up circuit for route relay R2HS, such pick-

up circuit extending from terminal B over back contact 79 of code relay RL2L at the other end of the route, back contact 80 of the opposing route relay L2HS, front contact 81 of signal repeater relay L2GP, front contacts 82 and 83 of switch repeater relays 3WPZ and 3NKP, respectively, front contact 84 of signal repeater relay R2GP, winding of route relay R2HS, and front contact 85 of code relay RR2L to terminal C. The picking up of relay R2HS completes the circuit network for signal control relay RA2H (Fig. 6) and that relay in turn on picking up causes the signal RA2 to be operated to a proceed position and signal repeater relay R2GP to be released. (Figs. 4 and 5.) The release of relay R2GP completes the stick circuit for relay R2HS, such stick circuit including terminal B, front contact 86 and winding of relay R2HS, a second front contact 87 of relay R2HS, back contact 88 of relay R2GP, back contact 89 of code relay NR2L and terminal C. Consequently when code relay RR2L is released at the end of the code impulse that selects that relay, the route relay R2HS is retained energized over its stick circuit providing the associated signal RA2 has cleared. In the event there is a failure in clearing signal RA2, then route relay R2HS is released at the end of the code and the code influence is annulled. That is, the apparatus assumes its normal condition and a new code must be transmitted in order to effect the control for signal RA2. In other words, the code is not stored and a "hidden lockout" condition cannot arise due to the failure of the signal to clear.

If traffic over this route on track EB with crossover 3 normal is to be established from signal L2, code relay RL2L is selected by the proper code and a pick-up circuit is formed for route relay L2HS from terminal B over back contact 90 of code relay RR2L at the other end of the route, back contact 91 of the opposing route relay R2HS, contacts 84, 83, 82 and 81, winding of relay L2HS, and front contact 92 of code relay RL2L to terminal C. As explained in connection with Figs. 4, 5 and 6, the picking up of route relay L2HS completes the network for signal control relay L2H which in turn causes signal L2 to be operated to its proceed position and signal repeater relay L2GP to be released. Release of repeater relay L2GP closes the stick circuit for relay L2HS from terminal B over front contact 94 and winding of relay L2HS, a second front contact 95 of relay L2HS, back contact 96 of relay L2GP and back contact 97 of code relay NL2L to terminal C. Hence route relay L2HS is retained energized subsequent to the release of code relay RL2L at the end of the code impulse providing relay L2H is picked up to clear signal L2 and release relay L2GP, but if such operation is not effected then route relay L2HS is released and the code control is annulled.

When crossover 3 is at its normal position route relays R8HS and L8HS are associated with the route of track WB between signals R8 and L8, and which relays are controlled by the associated code relays in substantially the same way as just explained in connection with the control of route relays R2HS and L2HS and the description for the control of route relays R8HS and L8HS need not be made in detail. It is to be noted, however, that the pick-up circuit for route relay R8HS includes back contact 98 of code relay RL8L at the opposite end of the route, back contact 99 of the opposing route relay L8HS and front contact 100 of the associated code relay RR8L;

and that the stick circuit for relay R8HS includes back contact 101 of signal repeater relay R8GP. Also that the pick-up circuit for route relay L8HS includes back contact 102 of code relay RR8L at the other end of the route, back contact 103 of the opposing route relay R8HS and front contact 104 of the associated code relay RL8L; and the stick circuit for relay L8HS includes back contact 105 of signal repeater relay L8GP.

10 In the case the crossover 3 occupies its reverse position to form the route from signal LB8 to signal RB2, route relays R2HS and L8HS are associated with the opposite ends of the route. Under such set-up of the track layout the pick-up circuit for route relay L8HS is formed from terminal B over back contact 90 of code relay RR2L, back contact 91 of route relay R2HS, front contact 84 of relay R2GP, front contact 106 of the reverse switch repeater relay 3RKP, front contacts 107 and 108 of relays 3WPZ and L8GP, respectively, winding of relay L8HS and front contact 104 of relay RL8L to terminal C. The stick circuit for relay L8HS includes back contact 105 of signal repeater relay L8GP, the same as previously pointed out. If traffic is to move from signal RB2, then route relay R2HS is selected by a pick-up circuit including back contact 98 of relay RL8L, back contact 99 of relay L8HS, contacts 108, 107, 106 and 84, winding of relay R2HS, front contact 85 of code relay RR2L and terminal C. The stick circuit for relay R2HS is completed at back contact 88 of signal repeater relay R2GP as previously traced.

35 Still referring to Fig. 7, the switch controlling relays 3NWS and 3RWS which control the position of crossover 3 as explained hereinbefore, are controlled by code responsive relays of the centralized traffic control system and which relays are shown as being included in the coding unit CU1. When a normal switch code relay N3L and a code delivery relay DR of unit CU1 are picked up in response to a particular switch code, a pick-up circuit is formed from terminal B over front contact 109 of relay N3L, front contact 110 of relay DR, winding of relay 3NWS and to terminal C, and relay 3NWS is energized and picked up. Relay 3NWS is retained energized subsequent to the code impulse over a stick circuit that includes terminal B, back contact 111 of relay DR, back contact 112 of relay 3RWS, front contact 113 of relay 3NWS, winding of the relay and terminal C. In like fashion reverse switch controlling relay 3RWS is energized over a pick-up circuit including contacts of the code relays R3L and relay DR and which pick-up circuit includes terminal B, front contact 114 of relay R3L, front contact 115 of relay DR, winding of relay 3RWS and terminal C. Reverse relay 3RWS is provided with a stick circuit including terminal B, back contact 116 of relay 3NWS, front contact 117 and winding of relay 3RWS and terminal C.

65 In describing the operation of the apparatus I shall assume that crossover 3 is at its normal position, track section 1T is unoccupied and that it is desired to move a train on track EB past signal RA2, it being further assumed that the signal and switch repeater relays are all properly energized and picked up. The operator transmits a code to select code relay RR2L of coding unit CU1, and which code relay on picking up completes the pick-up circuit for route relay R2HS (Fig. 7) and relay R2HS on picking up completes the network (Fig. 6) for signal control relay RA2H which in turn causes signal RA2 to

be operated to a proceed position and signal repeater relay R2GP to be released (Figs. 4 and 5). With relay R2GP released, the stick circuit for route relay R2HS is formed before the code relay RR2L releases, and the signal is retained at its proceed position to govern the traffic into the respective route. It is to be observed that should the operator desire to set signal RA2 to stop after having cleared the signal in the manner explained above, he can do so by transmitting a code that selects relay NR2L, which relay on picking up opening back contact 89, opens the stick circuit for route relay R2HS causing that relay to be released to open the circuit for the signal control relay RA2H. As explained hereinbefore, should there occur a failure in the operation of clearing signal RA2, then route relay R2HS is released at the end of the code and the code control is annulled with the result that a "hidden lockout" condition cannot arise. With signal RA2 cleared, and the train moving past the signal into section 1T, the track relay 1TR is shunted opening the network for the signal control relay RA2H (Fig. 6) causing the signal to be set to stop and the repeater relay R2GP to be reenergized, which latter relay on picking up opening back contact 88 opens the stick circuit for route relay R2HS and relay R2HS is released to its normal position. It is to be observed that approach locking relay R2M is controlled in the manner explained in connection with Fig. 3 and enforces the usual approach locking. It is also to be observed that while signal RA2 is cleared and relay R2HS held energized by its stick circuit, and if the operator inadvertently transmits a code for relay RL2L in an attempt to control relay L2HS to clear the opposing signal L2, such inadvertent operation does not cause relay L2HS to be picked up because its pick-up circuit is held open by back contact 91 of relay R2HS and also does not disturb the energized condition of the route relay R2HS because relay R2HS is held energized by its stick circuit.

If in place of clearing signal RA2 for a train on track EB, it is desired to establish traffic in the other direction past signal L2, then the operator transmits a code for selecting relay RL2L of unit CU2 to complete the pick-up circuit for route relay L2HS. Relay L2HS on picking up completes the network (Fig. 6) for signal control relay L2H and that relay on picking up causes signal L2 to be operated to a proceed position and repeater relay L2GP to be released. The release of relay L2GP completes the stick circuit for relay L2HS to retain the relay picked up and the signal at its proceed position subsequent to the release of the code relay RL2L. The operation of the apparatus associated with route relay L2HS is substantially the same as that described in connection with the operation of the apparatus associated with route relay R2HS. Furthermore, the operation of the apparatus and circuits associated with the route between signals R2 and L2 when the crossover 3 is at its normal position is substantially the same as the operation of the apparatus and circuits associated with the route between signals R2 and L2.

I shall next assume that it is desired to establish the route over the crossover 3 in reverse position. The operator would first transmit a code to control the reverse switch controlling relay 3RWS to bring about the reverse position of the crossover. Assuming the track sections 1T and 7T are unoccupied and the crossover is in its reverse position, and that it is desired to control

signal LB8 to its proceed position to move a train over the cross-over, the operator transmits a code for selecting relay RL8L to complete the pick-up circuit for route relay L8HS, such pick-up circuit being completed over front contact 106 of the reverse switch repeater relay 3RKP. Relay L8HS when picked up completes the control network for signal control relay LB8H (Fig. 6) and signal LB8 is operated to a proceed position and repeater relay L8GP is released. The release of relay L8GP completes the stick circuit for relay L8HS and that relay is retained energized subsequent to the code and signal LB8 is held at its proceed position. If it is desired to control signal RB2 to move a train over the crossover in its reverse position, code relay RR2L is selected to pick up route relay R2HS. The operation of the apparatus following the picking up of route relay R2HS is similar to that described in connection with controlling signal LB8 by route relay L8HS.

Again it is to be noted that if crossover 3 is normal and signal RA2 cleared in the manner explained hereinbefore and the operator by mistake attempts to reverse the crossover and clear signal LB8 for a move over the crossover, signal LA8, which would ordinarily clear by such a signal control with the crossover normal, cannot be cleared because of the deenergizing of the check relay 3WPZ.

It is to be seen, therefore, that I have provided railway traffic controlling apparatus incorporating novel means for controlling the signals at the opposite ends of a route over which traffic may move in either direction and by which apparatus the so-called "hidden lockout" condition cannot arise and a train cannot be directed through a wrong route.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a traffic route over which traffic may move in either direction, a signal at each end of the route to govern traffic over the route, a route relay for each end of the route effective when picked up to control the signal associated with the same end of the route to a proceed position, a signal repeater relay for each signal and picked up when the associated signal is at stop and released when the signal is at proceed, a manually controlled means for each end of the route and each of which means is operable to a normal condition and to an operated condition; a pick-up circuit for each route relay and each of which pick-up circuits includes a contact closed at the operated condition of the manually controlled means for the same end of the route as the route relay, a front contact of each of the signal repeater relays and a contact closed at the normal condition of the manually controlled means for the other end of the route; and a stick circuit for each route relay and each of which stick circuits includes a back contact of the signal repeater relay for the signal associated with the same end of the route as the route relay and a contact closed at the normal condition of the manually controlled means for the same end of the route.

2. In combination, a traffic route over which traffic may move in either direction, a signal at

each end of the route to govern traffic over the route, a route relay for each end of the route effective when picked up to control the signal associated with the same end of the route to a proceed position, a signal repeater relay for each signal and picked up when the associated signal is at stop and released when the signal is at proceed, a normal and a reverse manually controlled relay for each end of the route and each of which manually controlled relays is biased to a released position and is energized and picked up for a predetermined interval only in response to a pre-selected code; a pick-up circuit for each route relay and including a front contact of the reverse manually controlled relay for the same end of the route, a front contact of each of the signal repeater relays and a back contact of the reverse manually controlled relay for the other end of the route; and a stick circuit for each route relay and including a back contact of the signal repeater relay for the signal associated with the same end of the route as the route relay and a back contact of the normal manually controlled relay at the same end of the route as the route relay.

3. In combination, a traffic route over which traffic may move in either direction, a signal at each end of the route to govern traffic over the route, a route relay for each end of the route effective when picked up to control the signal associated with the same end of the route to a proceed position, a signal repeater relay for each signal and picked up when the associated signal is at stop and released when the signal is at proceed, a normally released code responsive relay for each end of the route and each of which code relays is adaptable of being picked up for a predetermined time interval and then released in response to a preselected code, a pick-up circuit for each route relay and each of which pick-up circuits includes a front contact of the code responsive relay for the same end of the route as the route relay and a back contact of the code responsive relay at the other end of the route, and a stick circuit for each of said route relays and each of which stick circuits includes a back contact of the signal repeater relay for the signal associated with the same end of the route as the route relay to retain the route relay energized only when the associated signal is operated to a proceed position during said predetermined time interval.

4. In combination, a traffic route over which traffic may move in either direction, a signal at each end of the route to govern traffic over the route, a route relay for each end of the route effective when picked up to control the signal associated with the same end of the route to a proceed position, a signal repeater relay for each signal and picked up when the associated signal

is at stop and released when the signal is at proceed, a first and a second manually controlled relay for each end of the route and each of which relays is biased to a released position and adaptable of being picked up in response to a code impulse of current of a predetermined duration, a pick-up circuit for each route relay and each of which pick-up circuits includes a front contact of said first relay for the same end of the route as the route relay and a back contact of said first relay for the other end of the route, and a stick circuit for each route relay and each of which stick circuits includes a back contact of the signal repeater relay and of said second relay for the same end of the route as the route relay whereby a route relay is picked up for clearing the corresponding signal to a proceed position and then retained picked up to retain the signal at such proceed position only if the signal is cleared during said predetermined duration, a signal can be set to stop in response to a code that picks up the associated second relay and operation of the first relay at the end of the route opposite a cleared signal is prevented from setting such cleared signal to stop.

5. In combination, a traffic route over which traffic may move in either direction, a signal at each end of the route to govern traffic over the route, a signal control relay for each signal effective when picked up to cause the signal to be operated to a proceed position, a route relay for each end of the route, a circuit for each said signal control relay to pick up the relay and each such circuits including a front contact of the route relay associated with the same end of the route and a contact controlled by traffic conditions of the route, a signal repeater relay for each signal and energized over a back contact of the signal control relay for the same signal, a normally released code responsive relay for each end of the route and each of which code responsive relays is picked up for a predetermined time interval in response to a preselected code and is then released when the code ceases, a pick-up circuit for each route relay and each of which pick-up circuits includes a front contact of the code responsive relay for the same end of the route as the route relay and a back contact of the code responsive relay at the other end of the route, and a stick circuit for each of said route relays and each of which stick circuits includes a back contact of the signal repeater relay for the signal associated with the same end of the route as the route relay to retain the route relay energized only when the respective signal control relay is picked up and the respective signal repeater relay is released during said predetermined time interval.

EARL M. ALLEN.
